DESIGN FOR A PEN AND PENCIL HOLDER

Edwin C. Moe, Lansing, Mich.

Application February 15, 1946, Serial No. 126,600

Term of patent 7 years

(Cl. D74—2)

To all whom it may concern:

Be it known that I, Edwin C. Moe, a citizen of the United States, residing at Lansing, in the county of Ingham and State of Michigan, have invented a new, original, and ornamental Design for Pen and Pencil Holders, of which the following is a specification, reference being had to the accompanying drawing, forming part thereof.

Fig. 1 is a front elevational view of a pen and pencil holder, showing my new design.

Fig. 2 is an end view.

Fig. 3 is a rear view.

I claim:

The ornamental design for a pen and pencil holder, as shown.

EDWIN C. MOE.
